UNITED STATES PATENT OFFICE.

FRANK G. LUDWIG, OF LOCKPORT, ILLINOIS.

COMMUTATOR-TRUING DEVICE.

1,076,217.

Specification of Letters Patent.

Patented Oct. 21, 1913.

Application filed May 31, 1913. Serial No. 771,039.

To all whom it may concern:

Be it known that I, FRANK G. LUDWIG, a citizen of the United States, and a resident of the city of Lockport, county of Will, and 5 State of Illinois, have invented certain new and useful Improvements in Commutator-Truing Devices, of which the following is a specification.

My invention relates to commutator truing devices and the object of this improvement is to provide a simple and effective device of this character which is normally held in engagement with the commutator by means of resilient members and locked out 15 of engagement with said commutator when not in use.

Other objects will appear hereinafter.

The invention consists in the combinations and arrangements of parts hereinafter described and claimed.

The invention will be best understood by reference to the accompanying drawing forming a part of this specification, and in which,

25 Figure 1 is a fragmental elevation of a motor equipped with my improvement which is shown in section, Fig. 2 is a view of the same taken on line 2—2 in Fig. 1, Fig. 3 is a side elevation of my improvement, and Fig. 30 4 is an enlarged section taken on line 4—4 in Fig. 1.

The preferred form of construction as illustrated in the accompanying drawing, comprises a bracket 5 secured to a boss 6 on the 35 frame 7 of a motor, or the like, by means of bolts 8, or their equivalent. Secured on the bracket 5 by means of a dove-tail connection is a base 9. The base 9 is maintained in position on bracket 5 by means of buttons 10. The buttons 10 are provided so that the base 40 5 may be moved longitudinally from its engagement with the bracket 5 when so desired.

Pins 11 extend upwardly from base 9 and 45 mounted on said pins 11 is an abrasive holder 12. Between the base 9 and abrasive holder 12 on each of the pins 11 is a compression spring 13 adapted to normally hold the abrasive holder in engagement with the 50 commutator 14 of the motor, or the like.

On the under side of the abrasive holder 12 is pivotally mounted a locking lever 15, pivoted as at 16. The end portions of lever 15 engage corresponding bevel surfaces 17 of 55 perforations 8 in plates 19, said plates 19 be-

ing secured to base 9 and engaging the sides of abrasive holder 12, substantially as indicated. The inclined surfaces 17 are oppositely inclined so that the lever 15 will always be in horizontal position, as will be readily understood. On the under sides of the abrasive holder 12 are provided leaf springs 20 adapted to hold the edges of an abrasive element 21, such as sand paper or emery cloth. The sand paper, or emery 60 cloth is placed on the upper curved surface of the abrasive element with its end portions bent around the edges thereof and held under the springs 20. The abrasive element 21 may extend entirely across longitudinally 65 of the face of the abrasive holder 12, or may be formed in a plurality of narrow strips with their ends held under the springs 20.

In operation, the device is secured to the 70 frame 7 of a motor, or the like, substantially as indicated, and when the device is to be used the lever 15 is placed in a position, such as indicated in Fig. 3, thus allowing the springs 13 to hold the abrasive against the commutator 14. When the device is not in use the lever 15 is moved on its pivotal point to substantially the position indicated by its dotted lines in Fig. 4, having moved over the inclined surfaces 17 of the plates 19 thereby drawing the abrasive holder toward 75 base 9, and upon lever 15 engaging the horizontal surfaces at the ends of the perforation 18, the abrasive is locked in inoperative position. All that is necessary to unlock the device is to simply move the lever 15 on its pivotal point. In use the 80 brushes, not shown, of the motor may be removed or raised from the commutator, or the device may be used while the motor is in use. When the brushes are positioned so 85 that they would interfere with the device when positioned as shown, the device may be secured to the frame by means of any suitable bracket to hold the device in such a position that it will not interfere with the 90 ordinary working of the brushes of the motor.

While I have illustrated and described the preferred form of construction for carrying my invention into effect, this is capable 95 of variation and modification without departing from the spirit of the invention. I, therefore, do not wish to be limited to the precise details of construction set forth, but desire to avail myself of such variations and 100 110

2
modifications as come within the scope of the appended claims.

Having described my invention what I claim as new and desire to secure by Letters Patent is:

- 5 1. A commutator truing device comprising a base in fixed position; guides on said base; an abrasive holder mounted on said guides; resilient elements between said abrasive holder and said base adapted to normally hold said abrasive holder in operative position; and a lock adapted to lock said abrasive holder in inoperative position, substantially as described.
- 10 15 2. A commutator truing device comprising a base in fixed position; guides on said base; an abrasive holder mounted on said guides; resilient elements between said abrasive holder and said base adapted to normally hold said abrasive holder in operative position; plates carried by said base and engaging said abrasive holder, said plates being provided with perforations with inclined sides; and a locking lever pivoted on said abrasive holder, engaging the inclined sides of the perforations in said plates and
- 20 25

adapted to lock said abrasive holder in inoperative position, substantially as described.

3. A commutator truing device comprising a base in fixed position; vertical guide pins 30 on said base; an abrasive holder mounted on said guide pins and adapted for vertical movement; a helical compression spring around each guide pin between said base and said abrasive holder normally maintaining 35 the latter in operative positions; plates carried by said base and engaging said abrasive holder, said plates being provided with perforations with inclined sides; and a locking lever pivoted on said abrasive holder, engaging 40 the inclined sides of the perforations in said plates and adapted to lock said abrasive holder in inoperative position, substantially as described.

In testimony whereof I have signed my 45 name to this specification in the presence of two subscribing witnesses.

FRANK G. LUDWIG.
